COMBINED BOTTLE AND CAP

Fred Ferdinand Morgan, Blonay, Switzerland, assignor to
Societe d'Assistance Technique Pour Produits Nestle
S.A., Lausanne, Switzerland

Filed May 14, 1973, Ser. No. 359,648

Term of patent 14 years

Int. Cl. D9—01

U.S. Cl. D9—163

Fig. 2

Fig.5

Fig. 3

Fig. 4

FIG. 1 is a side elevational view of a combined bottle and cap showing my new design, the other three sides being the same in appearance as the side shown;

FIG. 2 is a top plan view thereof;

FIG. 3 is a bottom plan view thereof;

FIG. 4 is a sectional view taken along lines 4—4 of FIG. 1; and

FIG. 5 is a sectional view of the cap only taken along lines 5—5 of FIG. 2.

I claim:

The ornamental design for a combined bottle and cap, as shown and described.
